UNITED STATES PATENT OFFICE.

JAMES G. HEASLET, OF PHILADELPHIA, PENNSYLVANIA, ASSIGNOR TO HIMSELF AND HARRY M. HART, OF PHILADELPHIA, PENNSYLVANIA.

FRICITION-CLUTCH.

SPECIFICATION forming part of Letters Patent No. 769,543, dated September 6, 1904.

Application filed November 14, 1903. Serial No. 181,123. (No model.)

To all whom it may concern:

Be it known that I, JAMES G. HEASLET, a citizen of the United States of America, residing in the city and county of Philadelphia, in the State 5 of Pennsylvania, have invented a certain new and useful Improvement in Friction-Clutches, of which the following is a true and exact description, reference being had to the accompanying drawings, which form a part thereof.

10 My invention relates to friction-clutches, and is especially adapted and intended for connecting together parallel shafts and for use in connection with automobiles, although obviously its uses may be widely extended.

15 The nature of my improvements will be best understood as described in connection with the drawings in which they are illustrated, and in which—

Figure 1 is a side elevation of the clutch 20 mechanism, taken as on the section-line 1 1 of Fig. 2; and Fig. 2 is a sectional view taken on the line 2 2 of Fig. 1.

A and B indicate the parallel shafts. In the construction shown the shaft A is formed 25 with a central recess A', which receives the reduced end B' of the shaft B, said shaft B being in this construction the power-shaft and having secured to its end through the hub C a plate C', which is shown as the web supporting a fly-wheel, (indicated at C'). The web or plate C' has secured to and extending 30 out from it studs, (indicated at D D,) which in turn support the longitudinally-movable sleeves, (indicated at E E,) said sleeves having shoulders at both ends (one indicated at E') formed by an outwardly-extending flange 35 of the hub, while the other shoulder (indicated at E') is preferably formed by a nut screwing on the end of the sleeve. To the end of the 40 other shaft, A, through its hub F is secured a friction-disk F', which by preference is formed or provided with two diverging elastic plates, (indicated at F' and F'.) One of the plates, as illustrated, is formed integrally 45 with the inner plate F', while the other, F', is secured to it by means of bolts, /.

G and G² are clamping-plates, which by means of perforated lugs G' and G² are secured on the sleeves E E, the one abutting

against the shoulder E', and the other moving 50 freely on the sleeve. The outer plate G² is also formed or provided with brackets G⁴ G⁴, which support pivot-pins on which turn the levers, (indicated at H H'.) The ends H' of said levers are forked and abut against the inside of 55 the shoulders formed by the nuts E', while the other ends, H H, of the levers rest in contact with the flange of an annular sleeve J, longitudinally movable along the shaft A and normally forced toward the clutch by a spring 60 K, abutted against a collar I.

It will readily be seen that the normal action of the spring K being to force the sleeve J toward the clutch will force the ends H H of the levers also toward the clutch, with the 65 result that the ends H H' are forced outward against the shoulders E', thus tending to draw the sleeves E E and the plate G outward, while the pressure of the levers on their pivot-pins forces the plate G² inward, thus clamping 70 the friction-plate between the two clamping-plates and coupling the two shafts together. I find it preferable to use the diverging elastic tongues in the friction-plate, though 75 it will be understood that these are not absolutely necessary. When it is desired to uncouple the shafts, the sleeve J is moved backward against the pressure of the spring K by any convenient means, with, of course, the result of permitting the plates G and G² to 80 separate and relaxing the frictional engagement of the parts.

Having now described my invention, what I claim as new, and desire to secure by Letters Patent, is—

1. A clutch for coupling parallel shafts consisting of a plate C', secured to the end of one shaft, in combination with studs D, D, extending from the outer face of said plate, sleeves E, E, supported on said studs and having shoulders E', E', at their opposite ends, clamping-plates G, G², supported on said sleeves, the outer plate G², having pivot-supporting brackets G⁴, G⁴, secured to it, a friction-disk F', secured to the end of the other 95 shaft and extending between plates G, G², levers H, H', H, H', pivoted on brackets G⁴, G⁴, and having their ends H', in contact with

shoulders E², of sleeves E and means for actuating the levers to engage and disengage the clamping-plates with the friction-disk.

2. A clutch for coupling parallel shafts consisting of a plate C', secured to the end of one shaft, in combination with studs D, D, extending from the outer face of said plate, sleeves E, E, supported on said studs and having shoulders E', E', at their opposite ends, 5 clamping-plates G, G², supported on said sleeves, the outer plate G², having pivot-supporting brackets G⁴, G⁴, secured to it, a fric-

tion-disk F', having diverging elastic flanges F², F³, secured to the end of the other shaft and extending between plates G, G², levers 15 H, H', H, H', pivoted on brackets G⁴, G⁴, and having their ends H' in contact with shoulders E² of sleeves E, and means for actuating the levers to engage and disengage the clamping-plates with the friction-disk.

JAMES G. HEASLET.
